(57) **CLAIM**

The ornamental design for a kitchen knife handle, as shown and described.

DESCRIPTION

FIG. 1 is a perspective view as seen from the left side of a kitchen knife handle showing my new design;

FIG. 2 is a left side view thereof, with the right side view being a mirror image thereof;

FIG. 3 is a bottom view thereof;

FIG. 4 is an end view thereof as seen from the knife blade end;

FIG. 5 is a cross sectional view thereof as taken along line 5—5 of FIG. 3;

FIG. 6 is a perspective view as seen from the left side of a kitchen knife handle showing a second embodiment of my new design;

FIG. 7 is a left side view thereof, with the right side view being a mirror image thereof;

FIG. 8 is a bottom view thereof;

FIG. 9 is an end view thereof as seen from the knife blade end; and,

FIG. 10 is a cross sectional view thereof as taken along line 10—10 of FIG. 8.

The dashed lines in the drawing illustrate environment and do not form a part of my design
